(57) **CLAIM**

I claim the ornamental design for a doll carrier, as shown and described.

DESCRIPTION

FIG. 1 is a rear view of a doll carrier showing my design in the position of use, the broken lines showing a child and doll in FIGS. 1 and 2 being understood to represent the portions of the design that form no part of the claimed design; FIG. 2 is a side perspective view thereof; and, FIG. 3 is a plan view thereof shown flat.

1 Claim, 3 Drawing Sheets

FIG - 1

FIG - 2

FIG - 3
